US0D1053726S

(12) **United States Design Patent** (10) **Patent No.:** **US D1,053,726 S**
(45) **Date of Patent:** **** Dec. 10, 2024**

(54) **WATCH**

(71) Applicant: **Anhui Huami Health Technology Co., Ltd.**, Hefei (CN)

(72) Inventors: **Wenjian Xu**, Hefei (CN); **Lian Liu**, Hefei (CN); **Chunyang Liao**, Hefei (CN)

(73) Assignee: **Anhui Huami Health Technology Co., Ltd.**, Hefei (CN)

(**) Term: **15 Years**

(21) Appl. No.: **35/517,271**

(22) Filed: **May 24, 2022**

(80) **Hague Agreement Data**

Int. Filing Date: **May 24, 2022**

Int. Reg. No.: **DM/221587**

Int. Reg. Date: **May 24, 2022**

Int. Reg. Pub. Date: **May 26, 2023**

(51) **LOC (14) Cl.** **10-02**

(52) **U.S. Cl.**

USPC **D10/32; D11/3**

(58) **Field of Classification Search**
